UNITED STATES PATENT OFFICE.

ANDREW DOUGHERTY, OF BROOKLYN, NEW YORK.

IMPROVEMENT IN PAPER-CUTTING MACHINES.

Specification forming part of Letters Patent No. 35,592, dated June 17, 1862.

To all whom it may concern:

Be it known that I, ANDREW DOUGHERTY, of Brooklyn, in the county of Kings and State of New York, have invented certain new and useful Improvements in Machines for Cutting Paper into Sheets; and I do hereby declare that the following is a full, clear, and exact description of my invention, reference being had to the accompanying drawings, in which—

Figure 1 represents a side elevation of a paper-cutting machine constructed according to the principles of my invention. Fig. 2 represents a vertical longitudinal section of the same. Fig. 3 represents a plan of the same, and Fig. 4 represents a side view of the knives detached from the machine.

My invention has reference to the cutting of paper into sheets, either as it is drawn from a roll or as it passes from a paper-machine. In such machines it is an object to deliver the paper rapidly to the cutter, so as to do a large amount of work, while, on the other hand, it is expedient, in order to insure uniformity in the length of the sheets, that the knife which makes the cut be not moved faster than a certain rate, determined by experience, which is much slower than the average speed at which the paper should be delivered. In order to obtain this relatively slow movement of the knife and average fast movement of the paper, machines have been devised in which the movement of the paper is arrested, in whole or in part, at the time it is cut.

My invention has reference to this class of machines; and it consists in combining the mechanism for operating the knives (which cut the paper) with the feed-rolls or their equivalents, (which deliver the paper to the knives,) by means of cam-formed cog-wheels, the large radius of one of which corresponds with the small radius of the other, the combination being such that while the knives are cutting the speed of the paper is reduced to a minimum, and need not be more than sufficient to compensate the bevel of the knives, so that the sheet is cut squarely across its breadth, as hereinafter described; but after the cut is effected the speed is progressively increased to a maximum, and then progressively decreased to the speed required during cutting, the average speed being that at which the paper must be delivered.

The object of the second part of my inven-

tion is to enable the paper to be cut in a straight line across the sheet; and it consists in combining the first part of my invention with an intermittent clamp, which grips the paper at the time the cut is made by the knives and prevents its movement, so that the paper is at rest while the knives are cutting, but at other times releases the paper and permits it to move freely through the machine.

The object of the third part of my invention is to prevent the end of the paper from which a sheet has been cut from adhering to the stationary knife; and it consists in combining the cutting mechanism with a bellows or other means of producing a blast of air to blow the end of the paper from the stationary knife, so that it may pursue its proper course through the cutting-machine.

The cutting-machine represented in the accompanying drawings is designed to be connected with a paper-machine, so as to cut the paper into sheets as fast as it is produced. The cutting is effected by means of a pair of knives which extend across the machine, one knife, *a*, being stationary in reference to the movement of the paper, and the other, *b*, being moved. The stationary knife *a* is secured to a stock, *C*, which rocks upon gudgeons in the frame of the machine. The moving knife *b* is secured to a revolving knife-stock, *D*, whose journals are supported in bearings in the frame, one of them being extended beyond the frame to receive the cog-wheel *f*, by which a rotary motion is imparted to the knife-stock and knife. The moving knife is beveled, so that in cutting its edge crosses that of the stationary knife, and the edges of the two cut like those of a shears. The cog-wheel *f*, connected with the stock of the moving knife, is driven by cog-wheels *e* *e*, the last of which is made fast to a driving-shaft, *i*, which has a belt-pulley secured to it that receives the driving-belt, so that the moving knife is caused to revolve continuously at a uniform speed. The stationary knife is pressed toward the axis of the stock of the moving knife by a pair of springs, *g* *g*, one at each of its ends, and the position which the stationary knife occupies with reference to the moving knife during cutting is regulated by a pair of cams, *h* *h*, which are secured to the extremities of the revolving knife-stock and act upon a pair of lugs, *m*, secured to the cor-

responding ends of the stock of the stationary knife. The cams *h* are of such form that during cutting the edge of the stationary knife is permitted to be borne by the springs *g* against the edge of the moving knife progressively from end to end, so as to insure a keen and certain shear, while the striking of the one edge upon the other at the commencement of the cut is prevented.

The paper to be cut is received into the cutting-machine by a pair of feed-rollers, *P* and *Q*, one, *P*, of which is pressed toward the other by springs *l*, so that the paper is gripped between the two. One of these rollers is driven at a uniform speed by means of a belt, *t*, which encircles pulleys secured, respectively, to the shaft of the roll and to the driving-shaft *i*, while the other roll, *P*, is caused to revolve by friction.

The paper is delivered for cutting with a varying speed by means of a second pair of feed-rolls, *T* and *U*, one, *T*, of which is pressed toward the other by springs, so that the paper is gripped between the two. The other roller, *U*, of the pair has a cog-wheel, *o*, secured to one of its gudgeons, and this cog-wheel is driven by means of other cog-wheels, *o'* and *o''*, the last of which is secured to a counter-shaft, *s*, that is parallel with the driving-shaft *i*. The counter-shaft and driving-shaft are fitted with cam-shaped cog-wheels *W* and *X*, having nearly the form of ellipses. These cog-wheels have the same number of teeth, and they are so set upon their respective shafts that the shortest radius of one corresponds with the longest radius of the other; hence as the driving-shaft *i* and the moving knife driven by it revolve at a uniform speed the speed of the delivery-rolls *T* *U*, whose revolution is determined by the cam-shaped cog-wheels, will be alternately fast and slow. The position of these cog-wheels is such that the slow motion of the delivery-rolls takes place when the knives are cutting, the shortest radius of the wheel *W* (upon the driving-shaft) then corresponding with the longest radius of the wheel *X* upon the counter-shaft, and the relative lengths of these two radii at that time are such that the paper is moved forward so as to keep the successive points of cut from one side to the other of the sheet in a line at right angles, or thereabout, with the direction in which the paper is delivered, so that whatever bevel is given to the stationary knife is compensated, and the line of cut is practically square across the sheet. When the cut is completed, the progressive change in the length of the radii of the cog-wheels which are in line causes the counter-shaft *s* and the delivery-rolls driven thereby to move with progressively increasing speed until the largest radius of the cog-wheel *W* on the driving-shaft corresponds with the smallest radius of that *X* on the counter-shaft, after which period the speed is progressively decreased to that required when cutting. As the receiving-rolls *P* *Q* revolve with uniform speed, while the delivery-rolls

T *U* revolve with a varying speed, the average of which is equal to that of the receiving-rolls, the paper between the two is alternately slackened and drawn up in order to hold the paper taut. Notwithstanding this slack, a supplementary roll, *Z*, is placed near the receiving-roll, and a dancing-roll, *N*, is arranged to rise and fall in guides between the supplementary roll and the lower receiving-roll, the paper being conducted round the rolls, as shown by the red line in Fig. 2, so that the dancing-roll takes up and gives out the slack as required.

The mechanism thus far described will cut paper sufficiently square across for many purposes; but as the paper is moving a little at the time of cutting, and as the stationary knife should be set slightly beveling to compensate this movement, the line of cut is slightly curved. In order that the line of cut should be straight across the sheet, the edge of the stationary knife is set at right angles to the length of the sheet, and a clamp is employed to grip the sheet of paper and hold it at rest during the operation of the knives upon it. This clamp in the present machine is formed by a vibrating block, *m*, suspended near its edge by pivots to the frame of the machine in such manner that its lower edge can be swung toward a stationary block, *c*, which is secured to the machine above the stationary knife. The ends of the clamp are fitted with springs *s*, which bear upon cams secured to the ends of the revolving knife-stock *C*, and these cams are of such form that just before cutting commences they act upon the springs and bear the clamp toward the stationary block *c*, between which and the clamp the sheet of paper is delivered. After the cut is made the cams permit the clamp to swing back by its weight and release the paper.

In order to carry into effect the third part of my invention in the machine represented, a bellows, *A*, is provided, and its nozzle is connected with a pipe, *n*, which extends parallel with the stationary knife. The side of this pipe nearer the stationary knife is perforated with a row of holes, through which the blast produced by the bellows is discharged over the stationary knife-blade against the sheet of paper extending upward therefrom. The blast is prevented from unduly expanding, and thereby becoming weakened before it strikes the paper, by the block *c*, between which and the upper surface of the knife the blast is discharged.

The bellows is operated by a cam (shown in dotted lines in Fig. 1) secured to the delivery-roll *U*. The cam operates the bellows to make the blast through the intervention of two levers, *d* and *z*, and the bellows-board is raised to draw in a new supply of air by means of a spring, *x*, acting through the intervention of the same levers. The cam is so set upon the delivery-roll that the blast of air is produced immediately after the cut has been effected, so as to detach the end of the paper from the

knife and cause it to pursue its proper course downward.

The sheets of paper as they are cut may be drawn off by hand, or may be received upon and delivered by a fly or dumb boy operating in the usual manner.

As the connection between the delivery-rolls of the machine and the knives is positive, the lengths of the sheets of paper cut are uniform, which, it is believed, is not the case with any cutting-machine heretofore used.

In order to change the machine to cut sheets of different lengths, a set of pairs of change-wheels should be provided, so as to vary the speed of the delivery-rolls to that of the moving knife.

Having thus described a paper-cutting machine embodying all parts of my invention, what I claim as my invention, and desire to secure by Letters Patent, is—

1. The combination of the mechanism for cutting the paper with the feed-rollers for delivering it to be cut by means of cam-formed cog-wheels, substantially as set forth.

2. The combination of the mechanism for cutting the paper, the feed-rollers, the cam-formed cog-wheels, and an intermittent clamp, substantially as set forth.

3. The combination of the knives of a paper-cutting machine with a bellows for producing a blast of air to detach the paper from the knives, substantially as set forth.

In testimony whereof I have hereunto subscribed my name.

ANDREW DOUGHERTY.
